UNITED STATES PATENT OFFICE.

HUGO MOCK, OF NEW YORK N. Y.

FAUCET.

Application filed April 20, 1922. Serial No. 555,741.

To all whom it may concern:

Be it known that I, HUGO MOCK, a citizen of the United States, residing at 930 St. Nicholas Avenue, New York, in the county 5 of New York and State of New York, have invented certain new and useful Improvement in Faucets, of which the following is a specification.

This invention relates to faucets for wash 10 basins and has for its object the provision of improved means for obtaining a flow of water in a single stream at any desired temperature.

Another object of the invention is to provide 15 means whereby the same effects can be produced with two independent hot and cold water faucets as with a combination hot and cold water faucet.

For many purposes the combination hot 20 and cold water faucet wherein the hot and cold water commingle before reaching the outlet of the faucet, has many advantages as by its use a supply of water for washing or bathing can be obtained of any desired 25 temperature from the coldest to the warmest. The objection to the combination faucet is partly its increased cost and partly its increased bulk as the combination faucet usually requires more room than the independent hot and cold water faucets. The 30 object of this invention is to provide a means for utilizing the separate hot and cold water faucets so as to get the effect of a combination faucet.

The invention is illustrated in a sectional view partly in elevation.

In the drawing 1 indicates a conventional wash basin, 2 a cold water faucet, 3 a hot water faucet. The outlet of the cold water 40 faucet A is considerably below the outlet of the hot water faucet B and the discharge spouts of these two faucets are so angularly disposed towards each other that the effect of the two streams meeting at the point 45 is to neutralize the impact of each other and to force the flow of water in a perpendicular rather than in an angular direction. In this way it is easy for the person using the wash basin to obtain hot water of any degree 50 of temperature without scalding or to modify the temperature of the cold water to any degree desired and it is possible by

this arrangement to wash the hands in a single stream of water obtained from both the hot and cold water faucets which is not 55 possible with the ordinary independent hot and cold water faucets hitherto known.

It is apparent also that where the independent faucets are positioned farther from each other at the rim of the wash basin than 60 is indicated in the drawing herein, then the angle formed by the spouts of the two faucets must be accordingly increased.

Having thus fully described my invention, what I claim is:

1. The combination of a basin, independent hot and cold water faucets placed at the upper rim of the basin adjacent each other, the outlets of said faucets being on different horizontal planes, and shaped and positioned relative to each other so as to deliver a single stream of water into the bottom of said basin when both faucets are open.

2. The combination of a basin, independent hot and cold water faucets placed at the upper rim of said basin adjacent each other and shaped and positioned relative to each other with their outlets disconnected and converging toward each other so as to deliver a single stream of commingled water 75 into the bottom of said basin when both faucets are open.

3. The combination of a basin, hot and cold water faucets positioned at the rim of said basin, each faucet having an independent angularly-disposed outlet, said outlets being disconnected and shaped and positioned at such relative angles to each other so as to deliver a substantially vertical stream of commingled water into the bottom 80 of said basin when both faucets are open.

4. The combination of a basin, hot and cold water faucets positioned at the rim of said basin, each faucet having an independent angularly-disposed outlet, said outlets being disconnected and shaped and positioned at such relative angles to each other so as to deliver a single stream of commingled water into the bottom of said basin 85 when both faucets are open.

In testimony whereof I hereunto affix my signature.

HUGO MOCK.
